UNITED STATES PATENT OFFICE.

RICHARD W. GERTZ, OF BROOKLINE, MASSACHUSETTS.

PIANO-ACTION.

1,353,905.

Specification of Letters Patent. Patented Sept. 28, 1920.

Application filed February 6, 1919. Serial No. 275,283.

To all whom it may concern:

Be it known that I, RICHARD W. GERTZ, a citizen of the United States, residing at Brookline, county of Norfolk, State of Massachusetts, have invented an Improvement in Piano-Actions, of which the following description, in connection with the accompanying drawing, is a specification, like characters on the drawing representing like parts.

This invention relates to piano actions and has for its object to provide a novel metal flange construction to which the hammer shanks are pivotally connected.

In order to give an understanding of my invention, I have illustrated in the drawing some selected embodiments thereof which will now be described, after which the novel features will be pointed out in the appended claim.

In the drawings, Figure 1 is a vertical sectional view through a piano action embodying my invention;

Fig. 2 is an enlarged plan view of the flange construction;

Fig. 3 is an enlarged sectional view on the line 3—3, Fig. 2;

Fig. 4 is a plan view of the flange member illustrated in Fig. 2;

Fig. 5 is a plan view of the retaining member shown in Fig. 2;

Fig. 6 is a view showing a modified form of the invention taken on the line 6—6, Fig. 7;

Fig. 7 is a plan view of the flange shown in Fig. 6.

In the drawings, 1 indicates a portion of the key frame of a grand piano on which the keys 2 are pivoted, and 3 indicates one of the action brackets which support the rails 4 and 5 that carry the flanges to which the hammer shanks 6 and wippens 7 are usually pivoted. Each wippen 7 is of usual construction and embodies a repetition lever 8 which coöperates with a stop screw 36.

These parts are or may be all as usual in grand piano actions and hence need no further description.

In my invention the flanges to which the hammer shanks 6 are pivoted are made of metal and each supports a stop screw 36. In order that the piano action may operate properly, it is, of course, necessary that the stop screws 36 should maintain their proper adjustment, for if any stop-screw loses its adjustment the piano action will not oper-

ate properly. I have provided herein a novel construction of metal flange which is provided with means for locking the stop screw 36 and thus preventing it from becoming loosened or losing its adjustment.

In the construction shown in Figs. 1 and 3, the flange member to which the hammer shank is pivoted is shown at 10 and it is in the nature of a small metal plate which rests on the top surface 11 of the rail 4 and fits at one end against the lip 12 thereof. Said flange member is clamped to the rail by means of a clamping screw 27. The other end of the flange projects beyond the rail 70 and is provided with the tongue 13 which enters between the arms 14 of the forked end of the hammer shank 6 and is provided with a groove 15 in which is received the pivot pin 16 by which the hammer shank is pivoted to the flange member. The pivot pin is fixedly clamped to the tongue 13 by means of a clamping plate or retaining member 17 which is clamped to said tongue by the clamping screw 37.

In order to lock the stop-screw 36 I provide the flange 10 with a slit 98 which intersects the screw-threaded aperture 97 through which the screw 36 passes. The aperture 97 is made with a slightly smaller diameter than that of the stop screw 36 so that when the stop screw is screw-threaded into the aperture said aperture is expanded or spread somewhat, thus producing a binding pressure on the top screw which prevents it from becoming loosened. The slit 98 is shown as extending to the screw-threaded aperture into which the clamping screw 37 is screw-threaded. The retaining member 17 is formed at its rear end with an enlarged aperture 94 through which the stop screw extends, said aperture being of sufficient diameter so that it does not engage the screw threads of the stop screw. The retaining member is shown as provided with suitable 95 ribs 95 for the purpose of strengthening it. The flange member 10 is shown as provided with a narrow or necked portion 93 immediately back of the slit 98 and the sides of said necked portion are bounded by vertical 100 flanges 92. The purpose of this necked portion is to accommodate a spanner or other tool which may be used for bending or adjusting the flange member so as to bring the hammer shank to which it is attached into 110 proper alinement.

In Figs. 6 and 7, I have shown a different

- construction in which the flange member indicated at 100 is formed with an enlarged aperture 88 immediately in front of the rail 4 through which an implement may be inserted for the purpose of bending the flange to bring the hammer shank into proper alinement. In this construction also the slit 98 is eliminated and the stop screw 36 is screw-threaded through both the flange and the clamping or retaining plate which is indicated at 170. By thus screw-threading the stop screw through both the flange and the retaining member, said stop screw is locked from turning movement.
- 15 It will be noted that the rear end of the clamping member is separated slightly from the flange, and hence when the clamping screw 37 is tightened, the downward pressure of said clamping screw will produce a downward pressure at the rear end of the retaining member so that the retaining member acts as a nut-lock for preventing the clamping screw from loosening.
- It will be noted that in both embodiments of my invention the means for locking the stop-screw 36 is entirely separate and independent from the clamping screw 27 by which the flange is clamped to the rail so that any stop screw may be adjusted if necessary without loosening the flange from the rail and without losing the adjustment which has been given to the flange. This

is highly advantageous because after any flange has once been secured on the rail and properly adjusted so that the corresponding hammer shank will be in perfect alinement, it is important that this adjustment should be maintained, for if the position of the flange is disturbed, then the hammer will not be perfectly alined and the tone of the piano will be thereby impaired.

I claim:

In a piano action, the combination with a supporting rail, of a flange member supported thereon and having a transverse groove, means for securing the flange member to the supporting rail, a pivot pin in said groove, a hammer shank pivotally connected to said pivot pin, a clamping member for retaining the pivot pin in the groove, means for securing the clamping member to the flange member, which means is entirely separate from the means that secures the flange member to the rail whereby the clamping member may be removed or replaced without disturbing the adjustment of the flange, a wippen provided with a repetition lever, and a stop screw for the repetition lever screw-threaded through the flange.

In testimony whereof, I have signed my name to this specification.

RICH. W. GERTZ.
